(57) **CLAIM**

The ornamental design for an angle grinder, as shown and described.

DESCRIPTION

FIG. 1 is a front perspective view of a design of an angle grinder;

FIG. 2 is a front elevation view of the angle grinder of FIG. 1; FIG. 3 is a rear elevation view of the angle grinder of FIG. 1; FIG. 4 is a first side elevation view of the angle grinder of FIG. 1;

FIG. 5 is a second side elevation view of the angle grinder of FIG. 1;

FIG. 6 is a top plan view of the angle grinder of FIG. 1; and, FIG. 7 is a bottom plan view of the angle grinder of FIG. 1. The broken lines shown in the figures depict environmental subject matter and form no part of the claimed design.

1 Claim, 6 Drawing Sheets
